UNITED STATES PATENT OFFICE

143,202

DESIGN FOR A DISPLAY STAND OR SIMILAR ARTICLE

Fred Frederics, New York, N. Y.

Application July 19, 1945, Serial No. 120,807

Term of patent 7 years

(Cl. D80—9)

To all whom it may concern:

Be it known that I, Fred Frederics, a citizen of the United States of America, residing in New York city, county of New York and State of New York, have invented a new, original, and ornamental Design for a Display Stand or Similar Article, of which the following is a specification, reference being had to the accompanying drawing, forming part thereof, wherein:

I claim:

The ornamental design for a display stand or similar article, substantially as shown and described.

FRED FREDERICS.
